APPARATUS FOR CONTROLLING THE OPERATION OF TALKING MACHINES OR
MACHINES IN TIMED RELATION TO A CINEMATOGRAPHIC MACHINE

Filed Nov. 29, 1920

FIG. 1.

FIG. 2.

INVENTOR

Frank Ernest Mosley

By Fannie, Davis, Marvin, & Edmonds
Attorneys

UNITED STATES PATENT OFFICE.

FRANK ERNEST MOSLEY, OF SHETTLESTON, SCOTLAND.

APPARATUS FOR CONTROLLING THE OPERATION OF TALKING MACHINES OR MACHINES IN TIMED RELATION TO A CINEMATOGRAPHIC MACHINE.

Application filed November 29, 1920. Serial No. 427,135.

To all whom it may concern:

Be it known that I, FRANK ERNEST MOSLEY, a subject of the King of the United Kingdom of Great Britain and Ireland, and 5 residing at Shettleston, Glasgow, Scotland, have invented a certain new and useful improvement in apparatus for controlling the operation of a talking machine or machines in timed relation to a cinematographic machine, of which the following is a specification.

This invention relates to a selector switch which may, for example, be driven from a cinematographic machine and which is 15 adapted to effect at the required times the starting and stopping of a sound reproducing machine or machines.

Fig. 1 of the accompanying drawing is an axial section and Fig. 2 a transverse section 20 of a switch according to the invention.

Referring to the drawing, 1 denotes a drum of insulating material fitted to a mandrel 2 fixed on a shaft 3 which in practice is 25 operatively connected with the film-feeding spindle of a cinematographic machine.

There is but one possible angular position of the drum 1 relatively to the shaft 3, the drum being secured in driving position by means of the boss 26 fixed on the driving 30 flange 27 and by the nut 28 threaded on a boss 29 of the drum-carrying mandrel 2 and pressing on the washer 30.

The selector switch proper includes a number of metallic rings 31 held in fixed angular relation to the drum 1 and separated by 35 rings 32 of insulating material; each of the rings 31 presenting on its periphery conducting segments spaced by segments of insulation, the latter being fitted into peripheral notches of the rings 31 and united by annuli of insulation, as shown in Fig. 2.

On the shaft 3 is a return conducting ring 33 interposed between two rings 34, 35 of insulating material.

45 The rings 31 are electrically connected to terminals 36 on the ring 33. Threaded into

each ring 31 is a conducting pin 37 sheathed in a tube 38 of insulating material led parallel to the axis of the shaft 3. The driving flange 27 is formed with pockets, one opposite each pin 37, and in each pocket is received a spring 39 urging a terminal 40 into contact with the head of the pin 37. Each terminal 40 is connected by a cable 41 laced through a rotatable bearing member 42 to 50 the corresponding terminal 36 on the ring 33.

Normally the terminals 40 protrude slightly from the inner face of the driving flange, so that, when the selector switch is slipped on to the mandrel 2 in correct position and 55 the nut 28 tightened up, the electrical connections will be completed without necessity for further manipulation.

I claim:—

A selector switch comprising, in combination, a rotary shaft, a driving flange on said shaft, said flange having pockets, a drum of insulating material adapted to be removably secured to said flange, a plurality of axially separable conducting rings fixed to said 60 drum and conjointly presenting a continuous surface of rotation, each ring comprising, 65 conducting and insulating segments spaced differentially apart, a return ring coaxial with said conducting rings, conducting pins 70 parallel with the axis of the shaft, said pins 75 electrically connected to the several conducting rings and disposed opposite the pockets in said flange, a set of spring-pressed terminals in said pockets engageable with said 80 pins, said terminals normally protruding beyond the face of said flange, a set of terminals in the return ring, and electrical connections between said sets of terminals.

In testimony whereof I have signed my 85 name to this specification in the presence of two subscribing witnesses.

FRANK ERNEST MOSLEY.

Witnesses:

ISABEL ROLLO,
FLORENCE HOUSTON.
